VALVE FOR PERCUSIVE TOOLS.

1,126,040.

Specification of Letters Patent.

Patented Feb. 2, 1915.

Application filed June 1, 1914. Serial No. 842,142.

To all whom it may concern:

Be it known that I, LEWIS C. BAYLES, a citizen of the United States, residing at Easton, in the county of Northampton and State of Pennsylvania, have invented a certain new and useful Improvement in Valves for Percussive Tools, of which the following is a specification.

This invention relates to valves for percussive tools, and more particularly to valves of the type thrown by compression generated in the cylinder by the piston at the end of its stroke in either direction.

The object of this invention is to provide a valve mechanism which will be simple of construction and be so balanced that a very slight degree of compression in the ends of the cylinder is required to throw it in either direction.

With this object in view, a valve mechanism has been devised, a practical embodiment of which is represented in the accompanying drawings, in which,

Figures 1 and 2 show longitudinal sections through the tool with the valve mechanism and piston in different positions.

In the drawings, the tool is shown as comprising a cylinder 1 in which reciprocates a piston 2. Near the front end of the cylinder is a valve bore 3 while near the back end of the cylinder is a valve bore 4. From the extreme forward end of the cylinder an inlet port 5 opens into the front end of the valve bore 3, while from the rear end of the cylinder a cylinder inlet port 6 opens into the rear end of the valve bore 4. From a point in the cylinder some distance farther from the front end than the port 5 a cylinder exhaust port 7 opens to the valve bore 3 through a port 8 in the rear end of the valve bore, slightly smaller in diameter than the valve bore, while from a point farther from the rear end of the cylinder than the port 6 a cylinder exhaust port 9 opens to the front end of the valve bore 4 through a port 10 in the front end of the valve bore 4 of smaller diameter than the valve bore. To the side of the valve bore 3 a slight distance rearward of the port 5 a valve bore inlet passage 11 leads from the fluid inlet port 12 of the tool, while to the side of the valve bore 4 a slight distance forward of the port 6 a valve bore inlet passage 13 also leads from the inlet port 12 of the tool. From the side of the valve bore 3 slightly forward of

its rear end, an exhaust passage 14 leads to the atmosphere, while from the side of the bore 4 slightly rearward of its forward end a second exhaust passage 15 also leads to atmosphere.

Sliding in the bores 3 and 4 are cylindrical valves 16 and 17 which may or may not be of the same diameter, it being preferable to have the valve 17 of slightly greater diameter than the valve 16, if any distinction is made. The valve 16 is slightly longer than the distance between the forward edge of the passage 11 and the rearward edge of the passage 14, while, similarly, the valve 17 is slightly longer than the distance between the rearward edge of the passage 13 and the forward edge of the passage 15. Between these valves and contacting therewith is a rod or pin 18 which slides through a longitudinal bore in the cylinder 1 and is of such length that when the valve 16 is seated against the upper end of its valve bore the valve 17 is likewise at the upper end of its valve bore, and, similarly, when one valve is in its lowermost position the other one will be also.

In operation, supposing the parts to be in the positions shown in Fig. 1, the air will enter through the port 12 and passage 11 in the forward end of the valve bore 3, passing through the port 5 into the forward end of the cylinder, and moving the piston rearwardly. The air from the rearward portion of the cylinder will exhaust through the port 9 and passage 15 to the atmosphere. It will be seen, therefore, that at the beginning of the backward stroke of the piston the only pressure on the valves will be on the forward face of the valve 16 so that the valve mechanism will be positively maintained in its rearmost position. As the piston moves rearwardly the first change in the pressure conditions on the valves will come when the front face of the piston passes the port 7. This will allow live pressure to pass to the port 8 and almost balance the live pressure on the forward end of the valve 16. This port 8 is, however, made slightly smaller in diameter than the valve bore 3, so that there will be a slight excess of effective pressure on the lower end of the valve 16, maintaining the valve mechanism in fixed position until it is necessary for it to be thrown. Shortly after the forward end of the piston passes the port 7 the rear-

ward end of the piston will cover the port 9, thus cutting off the exhaust from the rear end of the cylinder. As soon as this occurs pressure will commence building up in the 5 rear end of the cylinder from the momentum of the piston, this pressure being communicated to the rearward face of the valve 17 through the port 6. As the only pressure on the valve at this time is due to 10 the slight difference in area of the port 8 and the front face of the valve 16, the piston will have to travel only a very short distance before sufficient pressure is generated to throw the valve 17 forwardly, carrying 15 with it the valve 16, through the agency of the rod 18. This position of the parts is shown in Fig. 2. The method of operation on the forward stroke of the piston is merely the reverse of that already described and 20 need not be further detailed.

It will be evident that since the valves are each separately balanced by pressure on their ends, it is immaterial what their relative diameters are. It is preferable, however, to have the rearward valve of a little 25 greater diameter so that the valve will throw slightly more quickly at the end of the rearward stroke.

Although for simplicity of construction 30 the valves 16 and 17 are shown in separate pieces operated from each other by means of the rod 18, it is evident that they could be attached together if desired, and it is to be understood that while the present showing and description discloses only one specified 35 modification of the invention, other forms and modifications are included in the spirit and scope of the invention as expressed in the claims.

40 What I claim is:

1. In a fluid operated percussive tool, a cylinder, a piston, a valve bore for each end of the cylinder, ports leading from points at different distances from each end of the 45 cylinder to the ends of each valve bore, valves in said bores, inlet and exhaust ports for each of said valve bores alternately connected by said valves to the cylinder ports and means for moving one valve from the 50 other.
2. In a fluid operated percussive tool, a

cylinder, a piston, a valve mechanism for each end of the cylinder, comprising valve bores, cylinder inlet ports leading from the ends of the cylinder to ends of the valve bores, cylinder exhaust ports leading from points farther from the ends of the cylinder than said cylinder inlet ports, to the other ends of said valve bores, inlet and exhaust ports leading to and from said valve bores at points more distant from the ends of the valve bores than their respective cylinder inlet and exhaust ports, and means to move one valve from the other.

3. In a fluid operated percussive tool, a cylinder, a piston, a valve mechanism for each end of the cylinder, comprising valve bores, cylinder inlet ports leading from the ends of the cylinder to ends of the valve bores, cylinder exhaust ports leading from points farther from the ends of the cylinder than said cylinder inlet ports to the other ends of said valve bores, inlet and exhaust ports leading to and from said valve bores at points more distant from the ends of the valve bores than their respective cylinder inlet and exhaust ports, valves sliding in said valve bores and controlling the said valve bore inlet and exhaust ports, and means to move one valve from the other comprising a spacing rod between said valves.

4. In a fluid operated percussive tool, a cylinder, a piston, valve mechanism for each end of the cylinder comprising valve bores, cylinder inlet ports leading from the ends of the cylinder to ends of each of the valve bores, cylinder exhaust ports leading from points farther from the ends of the cylinder than said cylinder inlet ports to ports at the other ends of the valve bores, said ports being of smaller diameter than said valve bores, valve bore inlet and exhaust ports leading to and from the sides of said valve bores, valves sliding in said valve bores and controlling said inlet and exhaust ports, and means to move one valve from the other.

In testimony whereof, I have hereunto set my hand.

LEWIS C. BAYLES.
